KNITTING MACHINE

Alfred E. Ischinger, Reading, Pa., assignor to
 Textile Machine Works, Wyomissing, Pa., a corporation of Pennsylvania

Application December 6, 1937, Serial No. 178,226

21 Claims.

(CL. 66—96)

My invention relates to knitting machines, and particularly to improvements in the operation and control of bars and the like, such as the picot bars of full fashioned knitting machines.

In a full fashioned knitting machine, it has heretofore been usual to manually move a picot bar between an upper inactive position, out of the way of the narrowing combs, and a lower active position adjacent to the needles, in which latter position the points on the bar move between a plurality of locations relative to the needles, as in the dipping and shifting movements. Also, it has been heretofore suggested to automatically move a picot bar between active and inactive positions relative to the needles.

Such arrangements have various disadvantages which are overcome by my invention.

It is an object of my invention to provide novel means in knitting machines to effect the operation and control of bars and the like, such as the picot bars of full fashioned knitting machines, that is particularly adapted to automatic or partly automatic knitting machines.

Another object of my invention is to provide novel means in a knitting machine including cooperating elements which occupy a plurality of different active positions relative to each other, and in which the cooperating movements are automatically imparted to certain of the elements only when said elements are in one of the active positions.

Another object of my invention is to provide a novel knitting mechanism including one or more needle cooperating implements for movement between a plurality of locations when positioned for cooperation with the machine needle means, in one of which locations said implements have operative movement, and means is provided for locking said implements in each of said plurality of locations.

Another object of my invention is to provide novel cam, follower and detent means particularly adapted for knitting machines, in which the cam provides for continuous movement of the follower between active and inactive positions and between inactive and active relative to the cam, the detent holding the follower in the position considered as the inactive one and the cam operating means for releasing the detent.

Another object of the invention is to provide the above-mentioned features severally and in combination with each other, and with various other elements to effect certain new and useful results.

A further object of the invention is to provide

such novel means in a knitting machine that is simple and durable in construction, economical to manufacture and effective in its operation.

With these and other objects in view, which will become apparent from the following detailed description of the illustrative embodiment of the invention shown in the accompanying drawings, my invention resides in the novel elements, features of construction and arrangement of parts in cooperative relationship as hereinafter more particularly pointed out in the claims.

In the drawings:

Fig. 1 is a top plan outline view of intermediate sections of a multi-section full fashioned knitting machine embodying my invention, parts being omitted;

Fig. 2 is a view in front elevation of portions of the machine shown in Fig. 1;

Fig. 3 is a view, taken cross sectionally of the machine of Figs. 1 and 2, enlarged relative thereto;

Fig. 4 is a top plan view, on a larger scale and more in detail than Fig. 1 of the machine thereof, showing end and intermediate sections, parts being omitted;

Fig. 5 is a view cross sectionally of the machine, taken substantially along the line 5—5 of Fig. 2, enlarged relative thereto;

Fig. 6 is a detail view, enlarged relative thereto, of the mechanism viewed in the direction of the arrow F in Fig. 9;

Fig. 7 is a view of the upper right hand portion of Fig. 6, showing corresponding parts of a point shifting means in different positions;

Fig. 8 is a view of a portion of Fig. 7, toward the right hand side thereof, showing corresponding parts of the point shifting means in still further positions;

Fig. 9 is a view taken cross sectionally of the machine substantially along the line 9—9 of Fig. 6, but on a reduced scale relative thereto;

Fig. 10 is a view similar to Fig. 9, showing the parts thereof in different positions;

Fig. 11 is a detail sectional view taken along the line 11—11 of Fig. 10;

Fig. 12 is a view similar to Figs. 9 and 10 showing the parts thereof in further different positions;

Fig. 13 is a detail sectional view taken substantially along the line 13—13 of Fig. 6;

Fig. 14 is a detail sectional view taken substantially along the line 14—14 of Fig. 13;

Fig. 15 is a sectional view taken substantially along the line 15—15 of Fig. 6;

Fig. 16 is a sectional view taken substantially along the line 16—16 of Fig. 15;

Fig. 17 is a view of a lock mechanism of the invention, taken cross sectionally of the machine substantially along the line 17—17 of Fig. 2, enlarged relative thereto;

Fig. 18 is a detail front elevational view taken along the line 18—18 of Fig. 17;

Fig. 19 is a sectional view taken along the line 19—19 of Fig. 18;

Fig. 20 is a view similar to Fig. 19 of the parts thereof in different position; and

Fig. 21 is a detail sectional view taken along the line 21—21 of Fig. 19.

In the drawings and description, only those parts necessary to a complete understanding of the invention have been set forth; further information as to the construction and operation of other elements not herein specifically pointed out, but which are usual and well known, being available in the pamphlet entitled "Full Fashioned Knitting Machines," copyright 1920, and in the "Reading" Full Fashioned Knitting Machine Catalogues, copyright 1929 and 1935, published by the Textile Machine Works, Reading, Pennsylvania, and in a pamphlet entitled "Knitting Machine Lectures," published in 1935 by the Wyomissing Polytechnic Institute, Wyomissing, Pennsylvania.

This invention is particularly adapted for use in machines of the type illustrated in my Patent No. 2,101,048, issued December 7, 1937, but will perform its function in machines of various other types with equal efficiency.

Referring to Figs. 1 and 2, a machine for which the invention is adapted comprises center frames 17, a front beam 18, a back beam 19 and a front bed 21, constituting parts of a framework upon which the operating parts of the machine are mounted. Figs. 1 and 2 further show a main cam shaft 23, a picot bar shifting mechanism P, an auxiliary pattern control shaft A, a back narrowing shaft 24, a front narrowing shaft 21, picot points 28, on picot bars B, lever arms 29 pivotally mounting the bars B on picot bar shifting rods R disposed one at each side of the shifting mechanism P, picot bar raising and lowering devices E, locking devices L, and auxiliary pattern control chains for controlling the devices E and L, respectively.

Fig. 3 shows further, a center bed 25, and a pawl and ratchet mechanism C for rotating the auxiliary pattern control shaft A, journaled in brackets, such as the bracket 37 secured to a bar 38 fixed to the center frames 17. The device C comprises a ratchet wheel 39 fixed to the shaft A, a rocking member 42 pivotally mounted on the shaft A. A detent 43, pivotally mounted on a pin 44 in the bracket 37, and biased toward the ratchet wheel 39 by a spring 47 connected to a stationary part of the machine frame, operates to prevent backward turning of the ratchet wheel. A pawl 48, pivotally mounted on the rocking member 42 by a pin 49 operates in response to clockwise movement of the member 42, as viewed in Fig. 3, to advance the auxiliary pattern control shaft A. A detent arm 52, also pivotally mounted on the pin 44, cooperates with another ratchet wheel 53 fixed to the ratchet wheel 39, and has its teeth facing in reverse direction to the teeth of the wheel 39. A pin 54 on the detent 52 cooperates with a hook like finger 57 on the pawl 48 such that, as the pawl 48 is moved clockwise to advance the ratchet wheel 39, the finger 57 cooperates with the pin 54

64 to allow the arm 52 to engage a reverse tooth of the ratchet wheel 53, thereby preventing movement of the wheel 39 for more than one notch at each turning impulse of the member 42. The latter is connected by a pin 56 to one end of a link 59, the other end of which is connected by a pin 62 to the upper end of an upright arm 63 of a bell crank lever 64 pivotally mounted on a shaft 61, and having a generally horizontal arm 66 carrying a detent 69 at its free end forwardly of the machine. The arm 63 carries a roller follower 72 for cooperation with a cam 13 on the cam shaft 23.

A latch arm 74, pivotally mounted on a vertical pin 77 on the front beam 18, as shown in Fig. 3, is for holding the detent 69 and the arm 68 of the bell crank 64 in positions corresponding to the position of the follower 72 on the high point of the cam 13, to which the follower is moved by the cam, after an actuation of the ratchet wheel 39. A spring 78, connected between a hook 79 on the link 59 and a bracket 82 on the back beam 19, biases the follower 72 toward the cam 13, the detent 69 toward the latch arm 74, and the pawl 48 in reverse direction. The latch arm 74 is connected to a rod 83, along the front of the machine, for operation by a main pattern device M (Fig. 4), in a well known manner.

Fig. 3 also shows portions of a narrowing machine N, see Fig. 4, these portions being one arm 87, of several curved arms 87, 88 and 89, as seen in other figures, each fixed at one end to the back narrowing shaft 24 and carrying at its other end the front narrowing shaft 27. These arms are similar, but numbered 87, 88 and 89, because the arms 87 are plain, or of usual character, the arms 88 carrying portions of the raising and lowering devices E and the arms 89 carrying portions of the locking devices L, as will appear.

Also shown in Fig. 3, are a verge plate 92, sinkers 93, dividers 94, jacks 95, and a cock box 98 mounted on a guide rail 99.

The dividers 94 are moved forwardly and backwardly by a catch bar 102, which receives its movement, from a plain knitting cam 103 and a narrowing cam 105 on the cam shaft 23 through linkage comprising a cam follower 104, a back catch bar lever 107 on a shaft 108, and an upright lever 109 having an adjustable pivot 50 connection 112 to a horizontal lever 113. The follower 104 is biased toward its cams 103 and 105 by a spring 114 that is connected between a hook extension 117 of the catch bar lever 107 and a bracket 118 secured to the front beam 18. The sinkers 93 are engaged and disengaged by the catch bar 102 by means of a front catch bar linkage comprising a plain knitting cam 119 and narrowing cam 120, a cam follower 122, a front catch lever 123, a shaft 124, a link 127, a vertical lever 128, and a horizontal link 129.

Needles 132, two banks or sets of which are disposed between each pair of adjacent center frames 17, are held by clamps 133 to a needle bar 134 which is pivotally connected, by a bracket 137 fixed thereto, and a pin 138, to a lifting arm 139 on a needle bar lifting shaft 142, on which is mounted an arm 143 carrying a cam follower 144 on a shaft 147. The arm 143 is connected, by a spring 148, to a bracket 149 on the back beam 19. The follower 144 cooperates with a knitting cam 152 and a narrowing cam 151 on the cam shaft 23.

Forward and rearward movement of the needles is effected by a fork 153 fixed to the needle bar 134, and pivotally connected to a lever 154

having a notch 151 for resting the lever 154 on a pin 158 projecting from the side of a presser lever 159. The latter is carried by a presser shaft 162, and carries a follower 163 for cooperation with a presser cam 164 and a narrowing cam 165.

Dipping movements of the front narrowing shafts 27 about the axis of the back narrowing shaft 24 are effected by the downward and upward movement of links 167, each pivotally connected at its upper end to the front narrowing shaft 27, and at its lower end to a lever 168. Each lever 168 is pivotally mounted on the machine frame by a pin 169, and carries a follower 172 on a pin 173 for alternate cooperation, by shogging the cam shaft, with circular and contoured cams 174 and 177, respectively. Fig. 4 shows further a usual end stop mechanism S for cooperation with carrier rods 1-8, and a reinforced selavage attachment C.

As shown in Fig. 4, the main pattern device or unit M comprises a bracket 179 on the front beam 18, a sprocket wheel device 182 on a shaft 183 and a pattern chain 184. The chain 184 is supported along the front of the machine on idler rollers (not shown) secured to the front beam 18. A stub shaft 192 is supported in the bracket 179 transversely to the cam shaft. A tension spring 198, connected between a slide member 199 to which the stub shaft is fixed and a stationary hook 202 on the bracket 179, tends to move the stub shaft 192, whereby to move a follower 193 from an inactive position between shogging cams 194 and 197 to an active position, also between these cams, when it engages face-cam portions of the cams to shog the cam shaft 23. This tendency of the spring 198 is normally prevented by a latch which is released by a button on the chain 184. The stub shaft 192, and the follower 193 thereon, are returned to latched inactive position, against the action of the spring 198, by cooperation between a cam 207 on the cam shaft 23, and a follower 208 on the slide 199.

A narrowing head N, of which there are two, but only one is shown, comprises carrier nuts 209 mounted on a spindle (not shown) journaled in bearing blocks 212. Another spindle 214 controls point rods 217 and 218 (Figs. 5 and 6). The point rods 217 and 218 carry point combs 222 and 223, respectively, and are longitudinally slidably mounted in brackets 224, 225 and 226, carried by the front narrowing shaft 27.

The actuating mechanism for the narrowing head is of usual construction, comprising a ratchet device actuated by a lever 227 which, when the cam shaft 23 is shifted to the right, in the manner above described, engages a narrowing head actuating cam. The narrowing heads cooperate, in a usual manner, to control the position of the point or narrowing rods 217 and 218, and point combs 222 and 223 carried thereby, and also to control the traverse of the yarn carrier rods, in a well known manner. That is, the spindle 214 of the narrowing rods, and their associated devices, intermittently rack the narrowing fingers in each knitting section inwardly during the narrowing operations in the production of plain knit fabric, and the yarn carrier nuts 209 control the positions of end stops 229 to progressively decrease the traverse of the yarn carrier rods.

Mechanism (not shown), similar to mechanism 70 illustrated in my above mentioned patent may be employed to prevent the operation of the narrowing head mechanism N and the end stop mechanisms S by shifting the rollers on the levers 227, in instances where dipping movements of the

shaft 27 occur throughout the operation of the machine.

Referring to Fig. 5, a follower 232, for actuation by a picot bar shifting cam 233, and for riding on a circular cam 236 during plain knitting, is carried by a lever 234 that is secured to a shaft 237 in a bracket 238 on the back beam 19, and is acted upon by a spring 239, through another lever arm 235 on the shaft 237, to bias the follower 232 toward the cam 233. The spring 239 is connected between a hook 242, on the lever 235, and a bracket 243 secured to the back beam 19. An upright rod 244 is pivotally connected, at its lower end, by a pin 247 to the lever 235, and, at its upper end, is pivotally connected by a pin 248, to a lever 249 on the back narrowing shaft 24. The lever 249 is connected by a pin 252 to one end of a curved link 253 which is connected, at its other end by a pin 254, to a crank-like wedge lever, or picot bar shift actuator 257, pivoted on the front narrowing shaft 27. The front end of the actuator 257, see Figs. 6, 7 and 8, constitutes a wedge 258 for operation between adjustable contact elements 259, in the form of headed screws, screwed into the adjacent ends of the picot bar shifting rods R which are provided one for each half of the machine.

The rods R are normally biased longitudinally toward each other, and toward the wedge 258, by springs 262 coiled around the rods, each between one of the brackets 225, and an arm 263 secured to the shifting rods R and the picot bars B. Collars 264, adjustably fixed to the bars R, limit movement of the contact elements 259 toward the wedge 258, by engagement of the collars with brackets 267 which support guard members 268 for shielding the picot points in the upper, or inactive, positions thereof, as will be understood from Fig. 9.

Referring particularly to Figs. 9 to 15, each point rod bracket 225 has front grooves in which the point rods 217 and 218 are slidably fitted, substantially flush with the front face of the bracket, against which is secured an element 281 in the nature of a cover, or retainer for the rods, providing a slideway 288 for a rack 289, and functioning as a journal bearing for a pinion 290, longitudinally slidably mounted on the picot bar shifting rod R by a key 295 fixed to the pinion and located in a keyway 296 in the rod R.

At its upper end, each rack 289 carries a pin 293 disposed in the slot provided between the jaws of a bifurcate end 294 of a lever 297, thereby providing a lost motion pivotal connection between the rack 289 and the lever 297 which is pivotally mounted, intermediate its ends by a pin 298, on one of the curved arms 88 of the picot bar raising and lowering device E. The other end 299 of each lever 297 similarly is of bifurcate form having a lost motion pivotal connection, through a pin 302, to a plunger or rod 303 that is longitudinally slidably mounted in a bracket 304 on the back narrowing shaft 24, and carries at its lower end on a pin 307, a roller or follower 308 for cooperation with a camming chain 309 on a sprocket wheel 312 fixed to the auxiliary pattern control shaft A. The plunger 303 and the follower 308 are biased toward the chain 309 by a spring 314 connected between a pin 317 on the bracket 304 and a pin 318 on a sleeve 319. The latter surrounds the plunger rod 303 along which it is adjustably secured, as by screws 322, and acts as a lower limit stop to the downward movement of the plunger. This lower limit, as shown, is such that the follower 308

never rides on low links 325 of the chain 309. A latch or holding arm 323 is pivotally mounted by a pin 324 on the bracket 304 and carries a contact or shoulder element 327 for cooperation with a detent 328 on a bottom element 329 of the plunger 303 in which the pin 307 is journaled. A spring 332, connected between a pin 333 on the holding arm 323 and a pin 334 on the bar 38, biases the holding arm 323 toward a pin 337 protruding laterally from the side of a high link point 338 of the chain 309, which also has another high link or links 339.

The operation of the above-described picot bar raising and lowering mechanism E is such that, with the picot bar B in its uppermost position, as shown in Fig. 10, and the plunger 303 held in its uppermost position by the holding arm 323 and the chain 309 advancing clockwise, when the pin 337 engages and moves the arm 323 sufficiently, the contact element 327 releases the detent 328, whereupon, since the follower 308 is opposite the high link 338, it will, upon further movement of the chain, ride gradually downwardly to a position close to, but not touching, the low links 325. As the follower so moves, the plunger actuates the lever 297 to raise the rack 289, which action rotates the pinion clockwise about the rod R to lower the picot bar B from its upper or inactive position of Fig. 10 to its lower or active position relative to the needles 132 ready for the dipping action above described. After this action, and the horizontal shift action, completing the making of a picot course, the high link 339 raises the follower 308 whereby the holding arm 323 holds the plunger 303, the bar B, and the picot bar in upper positions, in which the picot points are shielded by the guard 268.

In the lower position of the bar B, the parts are positioned, as shown in Fig. 6, with the contact elements 259 in position for shifting movement by the wedge 258 to effect the horizontal or shifting action of the picot points. As the bar B is raised from its lower position of Fig. 6 to its upper position of Fig. 7, a collar 342, fixed to the rod R, as by a pin 343, and having a cam face 344, causes this face to engage a stationary pin or follower 347 on the cover element 287 of the bracket 224. This action forces the collar cam 342 and the picot bar shifting rod R to be moved axially to the left, as viewed in Figs. 6 and 7, against the action of the spring 262, from the position of Fig. 6, in which the contact elements 259 are within working range of the wedge 258, to the position of Fig. 7, in which the contact elements 259 are entirely out of range of the movement of the wedge, whereby to avoid having the picot bars shifted during narrowing by the combs 222 and 223. Thus, the picot bars are automatically rendered inactive during narrowing, as distinguished from prior machines in which this action is effected by hand.

As shown more clearly in Figs. 17 to 21, inclusive, each locking device L is somewhat similar in construction and operation to each picot bar raising and lowering device E above set forth, and comprises the bracket 226 having grooves in which the narrowing point rods 217 and 218 are slidably fitted, and against the front face of which bracket is secured an element 348 in the nature of a cover, or retainer for the rods, providing a slideway 349 for a locking bar or plunger 352, and constituting a journal bearing for the picot bar shifting rod R. A slide bearing plate or element 350 is secured to the bracket 226.

et 225 for the lock bar 352 between the bracket and the element 348, as by screws 351.

At its upper end, each lock bar 352 carries a pin 353 disposed between the jaws of a bifurcate end 354 of a lever 357, thereby providing a lost motion pivotal connection between the lock bar 352 and the lever 357, which is pivotally mounted, between its ends, by a pin 358, on the corresponding curved arm 89 of the locking device L. The other end 359 of each lever 357 is also of bifurcate construction having a lost motion pivotal connection to a pin 362 at the upper end of a plunger or rod 363 that is longitudinally slidably mounted in a bracket 364 on the back narrowing shaft 24, and carries, at its lower end, on a pin 361, a roller follower 368 for cooperation with a camming chain 369 on a sprocket wheel 372 fixed to the auxiliary pattern control shaft A. This plunger 363, and the follower 368, are biased toward the chain 369 by a spring 373 connected between a pin 374 on the bracket 364 and a pin 377 on a sleeve 378. The sleeve 378 surrounds the plunger 363 along which it is adjustably secured, as by screws 380, and acts as a lower limit stop to the downward movement of the plunger. This lower limit is also such that the follower 368 never touches, or rides on, low links 379 of the chain 369.

A latch or holding arm 382 is pivotally mounted by a pin 383 on the bracket 364, and carries a shoulder element 384 for position under a detent 387 on an element 388 near the bottom of the plunger 363 in which the pin 361 is journaled. A spring 389, connected between a pin 392 on the holding arm 382 and a pin 393 on the bar 38, biases the holding arm 382 toward a pin 394 extending laterally from the side of a high link 397 of the chain 369.

The lower end of the lock bar 352 is tapered or beveled to facilitate its easy entry between locking or dentent jaws 402 at the free end of an arm 403 having its other end 404 fixed to the picot bar shifting rod R, as by screws 407. The jaws 402 are lowered, from an upper inactive position of Fig. 20, to a lower active position of Fig. 19, by the rotation of the rod R by the rack 289, and the pinion 290, of the device E above set forth.

The operation of the locking device L is such that, with the picot bar B in its lower position, and the plunger 363 in its lower position as limited by the sleeve 378, when the chain 369 advances against the follower 368, the plunger 363 is elevated to lower the lock bar 352 to lock the latter to the jaws 402. At the same time, the holding arm 382 engages the detent 387 to latch the plunger 363 in its upper position.

During the time that the follower 368 is opposite the high link 397, the dipping and shifting movements of the picot bars B occur, which action causes the plunger and its associated parts to pivot about the axis of the back narrowing shaft 24. During this pivoting movement, the follower 368, being held by the arm 382, rides off the high link 397, and returns to this high link on the rise of the picot bar at the end of the picot forming operation. After this operation, the cam element or pin 394 releases the holding arm 382 for lowering of the plunger 363, and release of the lock element 352, when the follower 368 rides off the high link 397.

By the relation of the high links 338 and 339, on the chain 309, to the high link 397 on the chain 369, see Fig. 17, the locking device E is thereby actuated to locking position only during

the different operating movement of the picot bar represented by the dipping and shifting movements thereof, to avoid possible misalignment of the picot points with the needles under the tension of the fabric being knitted.

Of course, the improvements specifically shown and described by which I obtain the above results, can be changed and modified in various ways without departing from the invention herein disclosed and hereinafter claimed.

I claim:

1. In a straight knitting machine, a plurality of cooperating elements, means for imparting predetermined active movement to said elements relative to each other, means for imparting a second active movement to said elements relative to each other different from said first active movement, means for automatically moving said elements between active and inactive positions relative to each other, means whereby said two active movements are imparted to said elements when in active position only, said automatic means including a cam element, and a follower for said cam element, said cam element operating to provide for movement of said follower between active and inactive positions of the follower with respect to the cam element, and means for holding said follower in said inactive position.

2. In a full fashioned knitting machine, a needle bank, a narrowing machine, narrowing and lace points on said narrowing machine, a device for shifting said lace points, means for moving said lace points between active and inactive positions relative to the needles, means for automatically rendering said shifting means ineffective to shift said lace points in said active position, one of said means including a cam element, and a follower for said cam element, said cam element operating to provide for movement of said follower between active and inactive positions of the follower with respect to the cam element, and means for holding said follower in said inactive position.

3. In a straight knitting machine, needle means, one or more needle cooperating implements for movement between a plurality of locations when positioned for cooperating with said needle means and having operative movement while in one of said locations, means for locking said implement or implements in each of said plurality of locations, said locking means including a cam element, and a follower for said cam element, said cam element operating to provide for movement of said follower between active and inactive positions with respect to the cam element, and means for holding said follower in said inactive position.

4. In a straight knitting machine, a plurality of cooperating elements, means for imparting predetermined active movement to said elements relative to each other, means for imparting a second active movement to said elements relative to each other different from said first active movement, means for automatically moving said elements between active and inactive positions relative to each other, means for imparting said two active movements to said elements when in active position only, means for locking said elements in position during each of said active movements, said automatic means including a cam element, and a follower for said cam element, said cam element operating to provide for movement of said follower between active and inactive positions with respect to the cam, and means for holding said follower in said inactive position.

5. In a full fashioned knitting machine, a needle bank, a narrowing machine including a front narrowing shaft, a lever carried by said shaft pivotally mounted at one end adjacent thereto and carrying an element at the free end of the lever for cooperation with said needle bank, said lever being pivotally movable to move said element between an upper inactive position and a lower active position relative to the needles, means for automatically moving said lever from active position to inactive position and from inactive position to active position, means including an actuator for shifting said lever parallel to its pivot axis, and means responsive to downward and upward movement of said lever for moving the lever into and out of operative relation, respectively, to said actuator.

6. In a full fashioned knitting machine, a needle bank, a narrowing machine including a front narrowing shaft, a lever carried by said shaft pivotally mounted at one end adjacent thereto and carrying an element at the free end of the lever for cooperation with said needle bank, said lever being pivotally movable to move said element between an upper inactive position and a lower active position relative to the needles, means for automatically moving said lever from active position to inactive position and from inactive position to active position, means including an actuator for shifting said lever parallel to its pivot axis, and means including a cam and follower device responsive to downward and upward movement of said lever for moving the lever into and out of operative relation, respectively, to said actuator.

7. In a full fashioned knitting machine, a needle bank, a narrowing machine including a front narrowing shaft, a lever carried by said shaft pivotally mounted at one end adjacent thereto and carrying an element at the free end of the lever for cooperation with said needle bank, said lever being pivotally movable to move said element between an upper inactive position and a lower active position relative to the needles, pattern means, means for actuating said pattern means, means responsive to actuation of said pattern means for positively moving and controlling said lever from active position to inactive position and from inactive position to active position, means carried by said front narrowing shaft for locking said lever in its said lower position, and means for actuating said locking means.

8. In a full fashioned knitting machine, a needle bank, a narrowing machine including a front narrowing shaft, a lever carried by said shaft pivotally mounted at one end adjacent thereto and carrying an element at the free end of the lever for cooperation with said needle bank, said lever being pivotally movable to move said element between an upper inactive position and a lower active position relative to the needles, means for actuating said lever between said upper and lower positions, means carried by said front narrowing shaft for locking said lever in its said lower position, and means for actuating said locking means, each of said actuating means including a cam, a follower for the cam, and latching means controlled by the cam for causing the follower to occupy active and inactive positions relative to the cam at predetermined times.

9. In a full fashioned knitting machine, a needle bank, a narrowing machine, narrowing and lace points on said narrowing machine, means for shifting said lace points, pattern means, means for actuating pattern means, means re-

sponsive to actuation of said pattern means for positively moving and controlling said lace points from active position to inactive position and from inactive position to active position relative to the needles, and means automatically responsive to movement of the lace points to said inactive position for rendering said shifting means ineffective to shift said lace points and to movement of the lace points to said active position for rendering said shifting means effective to shift said lace points.

10. In a full fashioned knitting machine, a needle bank, a narrowing machine, narrowing and lace points on said narrowing machine, means for shifting said lace points, pattern means, means for actuating said pattern means, means responsive to actuation of said pattern means for positively moving and controlling said lace points from active position to inactive position and from inactive position to active position relative to the needles, and means for automatically rendering said shifting means ineffective to shift said lace points in said inactive position.

11. In a full fashioned knitting machine, a needle bank, a narrowing machine, narrowing and lace points on said narrowing machine, means for shifting said lace points, pattern means, means for actuating said pattern means, means responsive to the actuation of said pattern means for positively moving and controlling said lace points from active position to inactive position and from inactive position to active position relative to the needles, and means automatically responsive to movement of the lace points to said inactive position for rendering said shifting means ineffective to shift said lace points and to movement of the lace points to said active position for rendering said shifting means effective to shift said lace points.

12. In a straight knitting machine, needle means, one or more needle cooperating implements for movement between a plurality of locations when positioned for cooperation with said needle means and having operative movement while in one of said locations, pattern means, means for actuating said pattern means, means responsive to the actuation of said pattern means for positively moving and controlling said needle cooperating implement or implements from said position to an inactive position and from inactive position to said active position relative to said needle means, and means for locking said implement or implements in each of said plurality of locations.

13. In a straight knitting machine, needle means, one or more needle cooperating implements for movement between a plurality of locations when positioned for cooperation with said needle means and having operative movement while in one of said locations, pattern means, means for actuating said pattern means, means responsive to the actuation of said pattern means for positively moving and controlling said needle cooperating implement or implements from said position to an inactive position and from inactive position to said active position relative to said needle means, means for locking said implement or implements in each of said plurality of locations, and means for automatically actuating said locking means.

14. In a straight knitting machine, needle means, one or more needle cooperating implements movable between active and inactive positions relative to said needle means, pattern means, means including a follower for operative

relation to said pattern means to be controlled thereby for actuating said implement or implements, and means responsive to movement of said implements relative to said needle means from said active position to said inactive position for rendering said actuating means ineffective to actuate said implements while maintaining the follower in the plane of the pattern means.

15. In a full fashioned knitting machine, a needle bank, a narrowing machine, one or more needle cooperating implements mounted on said narrowing machine for movement relative thereto between active and inactive positions relative to said needle bank, pattern means, means including a follower for operative relation to said pattern means to be controlled thereby for actuating said implement or implements, and means responsive to said movement for rendering said actuating means ineffective to actuate said implements while maintaining the follower in the plane of the pattern means.

16. In a straight knitting machine, a plurality of groups of cooperating elements, means for imparting predetermined active movement to said groups relative to each other, means for imparting a second active movement to said groups relative to each other different from said first active movement, pattern means, means for actuating said pattern means, means responsive to actuation of said pattern means for positively moving and controlling one of said groups from active position to inactive position and from inactive position to active position relative to the other, means for imparting said two active movements to said groups when said one group is in active position only, and means for locking said one group of elements in position during each of said active movements.

17. In a straight knitting machine, loop forming means, one or more loop manipulating implements having predetermined active movement relative to said loop forming means, means for imparting a second active movement to said one or more implements which is different from said first active movement, pattern means, means for actuating said pattern means, means responsive to actuation of said pattern means for positively moving and controlling said one or more implements from active position to inactive position and from inactive position to active position relative to said loop forming means, means for imparting said two active movements to the implements when in active position only, and means for locking said implements in position during each of said active movements.

18. In a full fashioned knitting machine, a needle bank, a narrowing machine, narrowing and lace points on said machine for dipping movement thereby, means for shifting said lace points, pattern means, means for actuating said pattern means, means responsive to actuation of said pattern means for positively moving and controlling said lace points from active position to inactive position and from inactive position to active position relative to the needles, means for rendering said shifting means ineffective to shift said lace points in said inactive position, and means for locking said lace points in position relative to said narrowing machine during each of the dipping and shifting movements.

19. In a straight knitting machine, in combination, a group of knitting needles and a group of implements for operating on loops on said needles, a support for said implement group adapted for a certain cycle of movements, some

parallel to the plane of movement of said needles and others in a plane substantially at right angles to the plane of said some movements, a mounting for said implement group on said support adapted to hold the implement group in different positions in one of which the implements act on loops on the needles within the period of said cycle of movements of said support and in the other of which the implements do not affect the loops on the needles, means for moving said support through said cycle of movements, pattern means, means for actuating said pattern means, and means responsive to the actuation of said pattern means for positively moving said implement mounting from one of said positions to the other. 10

20. In a straight knitting machine, the combination as set forth in claim 19, together with

means for positively locking the mounting of the implement group in the position in which the implements will act on the loops during the movement cycle of the support, and means for releasing said locking means.

5 21. In a knitting machine, a member arranged to be moved through an operating cycle, detent means arranged to maintain said member inactive at one point in said cycle, means having a continuous surface controlling the movement of said member through its entire operating cycle, and means actuated by said latter means and arranged to release said detent means when said latter means is in cooperative relation with said member. 15

ALFRED E. ISCHINGER.

CERTIFICATE OF CORRECTION.

Patent No. 2,266,395.

December 16, 1941.

ALFRED E. ISCHINGER.

It is hereby certified that error appears in the printed specification of the above numbered patent requiring correction as follows: Page 4, second column, line 41, for "dentent" read --detent--; page 5, first column, line 44, claim 3, after "machine" and before "needle" insert a comma; line 47, same claim, for "cooperating" read --cooperation--; and line 56, same claim 3, for "mean" read --means--; and that the said Letters Patent should be read with this correction therein that the same may conform to the record of the case in the Patent Office.

Signed and sealed this 10th day of February, A. D. 1942.

(Seal)

Henry Van Arsdale,
Acting Commissioner of Patents.
